UNITED STATES PATENT OFFICE.

LAWRENCE HILDRETH, OF LEXINGTON, KENTUCKY.

DOOR-LOCK.

1,359,374.

Specification of Letters Patent. Patented Nov. 16, 1920.

Application filed October 11, 1919. Serial No. 329,999.

To all whom it may concern:

Be it known that I, LAWRENCE HILDRETH, a citizen of the United States, residing at Lexington, in the county of Fayette and State of Kentucky, have invented certain new and useful Improvements in Door- Locks; and I do declare the following to be a full, clear, and exact description of the invention, such as will enable others skilled 10 in the art to which it appertains to make and use the same.

My invention relates to improvements in door locks, and more particularly to those intended principally for use on automobile 15 doors, although the device is not restricted to any particular field.

The principal object of the invention is to provide a door lock of simple and inexpensive nature having novel means for holding 20 the bolt retracted while the door is open, and for releasing said bolt automatically when the door is closed, thus making it unnecessary to slam the door as must now be done.

25 A further object is to provide a lock of the above named type having a rocking control member and a bolt forming bill carried by said member, said bill being tapered for snug reception in a keeper to prevent rattling of the door.

In constructing the device, a novel form 30 of latch is carried by the control member for holding it in bolt releasing position, and a further object is to provide a single spring 35 for moving said latch to operative position when the lock is released, and for projecting the bolt when the door is closed.

Still further objects are to provide a trigger and link for releasing the latch when 40 the door is closed; to provide guiding means for said link on said latch; and to employ a single spring acting diagonally on said link for shifting it longitudinally and laterally for proper engagement with the latch.

45 With the foregoing in view, the invention resides in the novel construction and arrangement of parts hereinafter described and claimed, the descriptive matter being supplemented by the accompanying drawings which form a part of this application.

Figure 1 is an elevation of the interior parts of the lock showing them in position for securing the door closed.

Fig. 2 is a view similar to Fig. 1 showing

different positions of parts in full and dotted lines. 55

Fig. 3 is a detail elevation showing the manner in which the latch is released when the door is closed.

Figs. 4 and 5 are respectively horizontal 60 and vertical sections as indicated by lines 4—4 and 5—5 of Fig. 1.

Fig. 6 is a perspective view of the bolt or bill.

Fig. 7 is a vertical section on the plane of 65 line 7—7 of Fig. 2.

In carrying out my invention, I provide a rocking control member 1 which may well be in the form of a stub shaft having an appropriate handle 2. On this control member, I mount a bolt forming bill 3 which is spaced laterally therefrom and adapted for reception in an open keeper 4. I also use a latch 5 pivotally mounted at 6, said latch being adapted for holding the control member in bill releasing position, while a link 7 and a trigger 8 are provided for releasing said latch automatically when the door is closed. 70

The bill 3 may be mounted in any preferred 80 manner on the control member 1 and may also be of any desired construction. In the present showing however, the bill is formed by one end of a metal bar, this bar being bent to form two crank arms 9 and 10 and a bearing 11, the latter being secured by a rivet or the like 12 to the member 1, while the crank arms carry the remaining portion of the bar, which portion is preferably concentric with the member 1, though located 85 off the center thereof. The bill 3 is preferably tapered toward its free end as illustrated in Figs. 6 and 7 and it will thus snugly engage the keeper 4 to hold the door 90 against rattling. 95

The latch 5 may be mounted in any suitable manner, but I have shown said latch pivoted to a lateral arm 13 extending from the crank arm 9, said arm being preferably bifurcated for the reception of the latch as shown in Fig. 6. The latch may well be stamped from sheet metal and is provided with a shoulder 14 adapted to engage a relatively fixed stop 15 when the control member 1 is turned to lock releasing position. 100 When this takes place, the spring 16 which is connected to the latch 5 at a point spaced from its pivot 6, is placed under tension, 105

thereby shifting the latch to operative position and remaining under tension to project the bill 3 when the latch is released upon closing of the door. As shown, latch 5 is provided with a guide for the link 7, said guide preferably consisting of a lateral flange 17 having a vertical slot 18 in which the end of said link, remote from the trigger 8, is slidably received.

10 The upper edge of link 7 is formed with a shoulder 19 adapted for engagement with the flange 17 at the upper end of the slot 18, when said link is properly shifted by a spring 20, upon opening of the door. It 15 will be observed that the spring 20 exerts its tension diagonally of the link 7, thus not only sliding the latter longitudinally in the required manner, but shifting it laterally to engage the shoulder 19, with the corresponding shoulder of the latch 5, that is, the portion of the flange 17 at the upper end of slot 18.

The trigger 8 may be constructed in any adequate manner, but this part in addition 25 to the latch 5 and the link 7, may well be stamped from sheet metal as shown.

In the present form of the device, the trigger is provided with upper and lower trunnions 21 rotatable in fixed bearings 22, 30 said trigger having a crank arm 23 pivoted to the link 7, and a lateral wing 24 positioned to strike the keeper 4 when the door is closed. The rotary motion of the trigger 8 under the action of the spring 20, may well 35 be controlled by a stop 25 carried by the lowermost of the bearings 22, said stop being disposed in the path of the arm 23.

All the parts above described may be suitably incased and when used on automobiles, 40 will be housed within the door in the usual way. Regardless of the form of door on which the device is used however, it will be highly efficient and in every way desirable. The moment the knob 2 is turned sufficiently 45 to release the bill 3 from the keeper 4, the latch 5 moves downwardly against the tension of spring 16 and its shoulder 14 engages the stop 15, thus holding the controlling member 1 in bill releasing position. 50 When the door is now opened, spring 20 comes into play to shift link 7 into operative engagement with latch 5, at the same time rocking the trigger 8 in a manner to dispose its wing 24 in position to strike the keeper 4 55 when the door is again closed. When this closing is done, the trigger 8 is rocked on its journals 21, thus pulling upon link 7 in such manner as to release the latch 5, whereupon spring 16 comes into play to project 60 the bolt or bill 3 through the keeper 4. It will be observed that no slamming of the door is necessary, yet it will remain tightly closed and will be held against rattling, due to the taper of the bill.

65 Since probably the best results may be

obtained from the several details shown and described, they may well be followed. I wish it understood, however, that within the scope of the invention as claimed, the device may be embodied in forms other than that 70 shown.

I claim:

1. A door lock comprising a rocking control member, a bill carried by said control member for engagement with a keeper, latch 75 means carried by said control member for holding the same in bill releasing position, and releasing means for said latch means, including a trigger in position to strike the keeper.

2. A door lock comprising a rocking control member, a bill carried by said control member for engagement with a keeper, a pivoted latch carried by said control member and a stop with which it coacts for holding 85 said control member in bill releasing position, and releasing means for said latch means, including a trigger in position to strike the keeper.

3. A structure as specified in claim 2, together with a spring connected with said latch for engaging it with said stop and for rocking said control member to bill applying position when said latch is released.

4. A door lock comprising a rocking control member, a bill carried by said control member for engagement with a keeper, a pivoted latch carried by said control member and a stop with which it coacts for holding 95 said control member in bill releasing position, said latch having a guide, a latch releasing device received in said guide, and a trigger for operating said releasing device, said trigger being disposed to strike the keeper.

5. A door lock comprising a rocking control member, a bill carried by said control member for engagement with a keeper, a pivoted latch carried by said control member and a stop with which it coacts for holding 100 said control member in bill releasing position, a latch releasing link, coacting shoulders on said latch and link for engagement when said latch is set and the door opened, a trigger connected with said link 105 and disposed to strike the keeper, and spring means for shifting said trigger and said link to engage said shoulders when the door is opened.

6. A structure as specified in claim 5, 110 said spring means consisting of a spring connected with said link and exerting its tension diagonally thereon.

7. A door lock comprising a rocking control member, a spring projected bill concentrically carried by said control member and tapered to form a compensating agent to take up wear and prevent rattling, means for securing said control member in bill-releasing position before the door is opened, a trig- 115 120 125 130

ger mechanism operated when the door is closed, and means for engaging said trigger mechanism with the bill-retaining latch when the door is opened, whereby said latch and bill will be automatically released when the door is closed.

8. A door lock comprising a bolt for engagement with a keeper, a latch for holding said bolt in retracted position before the door opens, and a releasing device which connects with said latch when the door opens, said releasing device including a trigger disposed in position to strike and be actuated by the keeper.
- 10 9. A door lock comprising a bolt for engagement with a keeper, means for locking said bolt in retracted position before

any opening movement of the door, and means automatically operable upon closing of the door for releasing said holding means. 20

10. A door lock comprising a bolt for engagement with a keeper, means for locking said bolt in retracted position before any opening movement of the door, and releasing means for said holding means movable 25 independently of the latter for operative engagement therewith when the door is opened, said releasing means having a trigger disposed by the aforesaid movement in position to strike the keeper when the door is 30 closed.

In testimony whereof I have hereunto set my hand.

LAWRENCE HILDRETH.
